UNITED STATES PATENT OFFICE.

CHARLES COMSTOCK, OF RACINE, WISCONSIN.

CORNER-IRON FOR WAGON-BODIES.

SPECIFICATION forming part of Reissued Letters Patent No. 10,111, dated May 9, 1882.

Original No. 234,853, dated November 30, 1880. Application for reissue filed February 18, 1882.

To all whom it may concern:

Be it known that I, CHARLES COMSTOCK, of Racine, in the county of Racine and State of Wisconsin, have invented certain new and useful Improvements in Corner-Irons for Wagon-Bodies; and I do hereby declare that the following is a full, clear, and exact description thereof.

My invention relates to corner-irons for wagon-bodies and will be fully described hereinafter.

In the drawings, Figure 1 is a perspective view of the inside of a wagon-box corner embodying my invention. Fig. 2 is a detail and Fig. 3 is an outside view.

The body A is of ordinary construction, having inner side rails, B, and outer ribs, b b, posts C C supporting the ends of the side rails.

The outer portion of the corner-iron E may be of malleable cast-iron or any other suitable metal, and is provided with corrugations b' b' to correspond with the ribs on the body.

D is a binding-piece, having flanges c and d. The flange c is shorter than the binding-piece proper and fits between the side rails, which are shouldered down for that purpose, while the flange d fits between the ends of the sides of the body. Bolts passed through holes in the binding-piece, through the side rails,

posts C C, the sides of the wagon, and iron E bind the whole together so tightly as to prevent water from collecting in the joints. Screws e e will now serve to fasten the iron E to the sides and bottom rail, the ends of the ribs on the former joining with the corrugations on the iron to give a proper finish to the body, the corrugations abutting against and supporting the ribs. The ordinary facing-iron will cover the space between the top of flange d and the iron E, and the whole will form a complete and well-finished corner.

What I claim is—

1. A corner-iron, E, for wagon-bodies, having corrugations b' b', in combination with binding-piece D, having flanges c d and suitable bolts, whereby the end portions of the body are clamped between the corner-iron and the binding-piece, as set forth.

2. A corner-iron in combination with a clamping-piece, D, having flanges c d and suitable securing-bolts, as set forth.

In testimony that I claim the foregoing I have hereunto set my hand this 19th day of January, 1882.

CHAS. COMSTOCK.
